PACKAGE

Peter Grabler, Rocky River, Ohio, assignor to
 L. E. Shunk, Akron, Ohio

Application March 26, 1934, Serial No. 717,324

10 Claims. (Cl. 206—1)

This invention relates to a package and particularly to a package for flexible articles.

An object of my invention is to provide a package of sheet material deformed in a manner to 5 thoroughly seal it but openable by hand without tools even though the sheet material be metal of considerable thickness.

Another object of my invention is to provide a sealed package for flexible articles which may be 10 opened by hand by twisting the entire package.

Another object of my invention is to provide a package which may be made of relatively light 15 deformable material, such as metal foil, but which by reason of its form will retain its shape even though the article encased in the package is quite flexible.

Other objects include the arrangement of the package in such form that it may be easily and 20 cheaply constructed with the contents assembled therein.

In the drawing and description I have illustrated and described preferred embodiments of 25 my invention and the essential features are summarized in the claims.

25 In the drawing Figs. 1, 2 and 3 are diametrically extending sections through three modifications, Fig. 3 being a view along the line 3—3 of Fig. 4; Fig. 4 is a plan view of the package of Fig. 3; Fig. 5 is a perspective view of the package of Fig. 1 30 which has been twisted to open it; while Fig. 6 is a perspective view of a portion of still another modified form.

35 My invention comprises in general the provision of a package for an article or articles which are inherently unable to maintain a rigid shape, the package being preferably formed of light sheet material which may or may not be capable of remaining rigid when in the flat sheet form. My invention also provides a substantially rigid package even when the packaging material is so light 40 as to be incapable of remaining rigid when in sheet form. Such materials include metal foils of .005 inch thickness and less. It is desirable to package certain articles with very light materials for ease in handling, but such packages are 45 of little value unless the article is tightly sealed and protected against harmful agents, and unless the package retains its shape when handled and is easily openable, preferably without tools.

50 My package comprises, in general, a pair of covers of deformable sheet material adapted to be twisted by hand. Each cover has a substantially flat central portion surrounded by a raised portion bent outwardly from the central portion 55 and away from the enclosed article then bent

back again toward the enclosed article and beyond the plane of the central portion. The free edge of one cover then overlaps the free edge of the other cover and is spun or otherwise permanently deformed thereover in embracing relation. 5 The raised rims of the covers strongly reinforce the sheet material and the package is further guarded against deformation by the overlapping and overspun edges. A package so formed is very light in weight and is tightly sealed against 10 dirt and other foreign matter. The covers will not come apart by a straight pull longitudinally, nor by ordinary handling. However, by manually twisting the entire package in the hands, the spun edges are easily forced apart for removal of the 15 article. This twisting is the more easily accomplished because the packaged article is flexible and the packaging material is light enough to be deformable by hand.

20 In the various views of the drawing the package comprises covers 10 and 11 having substantially flat central portions 12 surrounded by raised portions 13. The raised portions are bent outwardly at 14, then inwardly at 15 to extent beyond the planes of their respective central portions 12. 25 The edges of the covers overlap as at 16 and the free edge of one is bent or spun over the edge of the other cover in embracing relation. It will be understood that the thickness of the cover material is greatly exaggerated in the drawing. 30

35 The covers are cut and formed from sheet material which is deformable, that is to say, material which has the characteristic of retaining the shape given to it in the forming operations. The material should be of such a nature that it 40 may be twisted by hand if all of the advantageous features of my invention are to be realized. Suitable materials comprise metal sheets, particularly metal foils, and treated papers and cellulose compositions. Metal sheets and foils are suitably formed in dies by pressure alone but some of the other materials require heated 45 dies. The details of such die-forming operations are well known to persons skilled in the art. My preferred method of constructing the package is to pre-form each cover, to then place the packaged article in the lower cover, as seen in Fig. 1, and thereafter to place the upper cover thereover and bend its edge over the edge of the bottom cover.

50 This form of package is specially adapted to contain a flexible article having a flat central portion surrounded by a thick annular ring. This would include rubber articles such as finger cots and similarly shaped articles for the pre- 55

vention of disease. This form of article is indicated at 18 in Fig. 1. In this case the flat central portions 12 of the covers are circular and correspond in extent substantially to the flat central portion 19 of the article and are spaced apart to accommodate the article. The annular portion 13 of each cover is substantially complementary to half the annular ring 20 of the article as divided along a plane parallel to the central portion of the article.

10 This package is designed especially to contain flexible articles which are inherently incapable of maintaining a rigid position. This might include the flexible rubber articles mentioned above or it might include a plurality of small loose articles.

15 Due to the particular form of the package it will retain its shape under average conditions even though constructed of sheet material ordinarily not rigid in plain sheet form, such for instance as a metal foil of .005 inch in thickness or less. Such a foil makes an attractive package of very light weight. The combined annular portions 13 of the two covers, when assembled, 20 provide substantially a continuous tube about the periphery of the package which greatly rigidifies the same. Additional reinforcement is supplied by the double ring of lapped and over-spun material at 16.

25 30 The modification of Fig. 2 is similar to Fig. 1 in most respects and the parts are similarly numbered. In this case the inwardly bent portions 15 of the annular cover portions 13 have their extreme edges offset radially outward as at 35 21. The offset edge of one cover is then spun over to engage beneath the offset edge of the other cover as indicated at 22. This construction is more rigid than that of Fig. 1 because of the outwardly extending circumferential rib formed 40 by the two overlapped and interengaged offset edges of the covers.

45 The modification of Figs. 3 and 4 is similar to Fig. 2 with the addition of rigidifying ribs provided in the flat central portion of one or both covers. It is obvious this construction could be added to the form shown in Fig. 1, if desired. The rib-like deformations may be variously formed but I prefer those shown at 23 which extend radially from the annular portion 13 to a 50 central point, such as 24. This construction is even more rigid than that of Fig. 2 and insures against the central portions 12 of the covers being easily pressed inward against the central portion of the packaged article or articles.

55 60 The packages shown in Figs. 1 to 5 are circular in plan, and, in certain respects such a shape gives greater rigidity to the package than other shapes would. However, many of the advantages of my invention are realized in packages 65 of any desired plan, such as the rectangular form illustrated in Fig. 6. Parts which function somewhat similarly to the parts of Figs. 1 to 5 have similar reference characters with the suffix "a". The raised portions 13a form substantially a tube about the central portions 12a and the overlapping and spun-together edges at 70 65 16a give additional reinforcement. The ribs 23a may run transversely as shown, or to a central point, similar to Fig. 4, or may be omitted entirely.

75 It will be evident that a package constructed as taught by any of the illustrated forms will be tightly sealed against the entrance of foreign matter in such a manner that the covers cannot be easily removed by a pull normal to the

central portions. Nor will such a package be easily opened by inserting a finger nail beneath the overlapping covers because in practice the covers will be of very thin material and tightly pressed together. However, the package may be easily opened without tools simply by twisting it in the hand, as illustrated in Fig. 5, which is the more easily accomplished because the packaging material is light and the packaged article is flexible. Such a twist will force one 10 spun edge over its overlapped coating edge, as indicated at 25, even though the package be constructed of fairly heavy gauge metal.

15 What I claim is:

1. A package comprising a pair of covers of 15 metal foil on opposite sides of a packaged article, each cover having a substantially flat central portion surrounded by a raised portion bent first outward away from the article, then bent back toward the article and beyond the plane of the 20 central portion, and the free edges of the covers being overlapped with the edge of one cover spun over upon the edge of the other cover in embracing relation, said raised portions being of a height to exert a reinforcing effect on the package as a 25 whole and to furnish tightly embracing edges forming a sealed joint of considerable strength.

2. The package of claim 1 in which the overlapped edges are offset outwardly in a plane parallel to the central portion of the covers to form 30 a rib extending peripherally about the package.

3. The package of claim 1, in which the central portion is provided with upstanding ribs to increase its rigidity.

4. A package for a flexible article comprising 35 a pair of circular covers of metal foil adapted to be twisted by hand, each cover having a substantially flat portion and an annular portion surrounding the flat portion and raised thereabove, and the outer free edge of the annular portion of one cover being pressed tightly against and spun over upon the outer free edge of the other cover, whereby the package is tightly sealed but openable without tools by twisting in the hands, said 40 annular portions being of a height to exert a reinforcing effect on the package as a whole and to furnish tightly embracing edges forming a sealed joint of considerable strength.

5. A package for a flexible article comprising 45 a pair of circular covers of metal foil adapted to be twisted by hand, each cover having a substantially flat central portion and an outwardly bending annular portion surrounding the central portion and raised above it, and the outer free edge of the annular portion of one cover being bent 50 toward and spun over upon the outer free edge of the annular portion of the other cover, whereby the covers may be separated without tools by twisting the entire package to force the spun edges apart, said annular portions being of a 55 height to exert a reinforcing effect on the package as a whole and to furnish tightly embracing edges forming a sealed joint of considerable strength.

6. A package for a flexible article comprising 60 a pair of circular covers of metal foil adapted to be twisted by hand, each cover having a substantially flat central portion and an outwardly bending annular portion surrounding the central portion and raised above it, said annular portions 65 being substantially semi-circular in section, and the outer free edge of the annular portion of one cover being bent toward and spun over upon the outer free edge of the annular portion of the other cover, whereby the covers may be separated with- 70 75

out tools by twisting the entire package to force the spun edges apart, said annular portions being of a height to exert a reinforcing effect on the package as a whole and to furnish tightly embracing edges forming a sealed joint of considerable strength.

7. The package of claim 4, in which the flat portion of at least one cover is provided with rib-like deformations.

10. 8. A package comprising a pair of circular covers of metal foil, each cover having a substantially flat central portion surrounded by an annular portion, said annular portion extending in a smooth curve axially outward on one side of the plane of said central portion then axially inward beyond the plane of said central portion, the free edges of the covers being overlapped with the edge of one spun over upon the edge of the other in embracing relation, and the flat portion of at least one cover having raised deformations extending radially from the annular portion to a central point, said annular portions being of a height to exert a reinforcing effect on the package as a whole and to furnish tightly embracing edges forming a sealed joint of considerable strength.
15. 9. A package for a flexible article comprising a pair of circular covers of metal foil not substantially over .005 inch in thickness, each cover

having a substantially flat central portion surrounded by an annular portion, said annular portion being bent outward on one side of the plane of said central portion then inward beyond the plane of said central portion, and the free edges of the covers being overlapped with the edge of one spun over upon the edge of the other in embracing relation, whereby said annular portions and said overlapping spun edges reinforce said foil material and maintain substantial rigidity of 10 said package.

10. A package comprising a pair of covers of sheet material adapted when grasped in the hands to be twisted and destroyed, said covers being adapted to be placed on opposite sides of a packaged article, each cover having a substantially flat central portion surrounded by a raised portion bent first outward away from the article, then bent back toward the article, and the free edges of the covers being overlapped with the edge of 20 one cover bent over the edge of the other cover in embracing relation preventing separation of said covers in a direction normal to the plane of said central portion, said raised portions being of a height to exert a reinforcing effect on the package as a whole and to furnish tightly embracing 25 edges forming a sealed joint of considerable strength.

PETER GRABLER.
